UNITED STATES PATENT OFFICE

2,592,398

STAPLING MACHINE

Jay N. Edmondson, Harry Poulos, and Clarence
R. James, Columbus, Ohio

Application June 14, 1950, Serial No. 167,952

3 Claims. (Cl. 1—3)

1

This invention is a novel mechanism constructed into a stapling machine to cause staples contained in a carrier or magazine to be driven into wood, rubber, steel, or other material, or against a die for the purpose of clamping material together, expressly designed to cause the staple to be driven and ejected either in a plane parallel to its original position, or to a position angular to its original position in the magazine.

The invention embodies novel means for selecting and causing ejection of the staple to either of the two previously mentioned positions. These means are illustrated in the accompanying drawing, in which we have shown the design which permits either parallel ejection of the staple, or ejection at ninety degrees to its original position. While we have shown therein a preferred embodiment, it is to be understood that the same is susceptible to modification and change, and comprehends other details, arrangements of parts, features and construction, without departing from the spirit of the invention.

In the drawings:

Fig. 1 is an illustration of the mechanism, partly in section to show details of construction, and staples indicated at X and Y to illustrate the possible ejected positions of the staples in this design.

Fig. 2 is a view in vertical cross-section.

Fig. 3 is a bottom view of the freely rotatable staple driving guide-way element.

Fig. 4 is a plan view of the cam cylinder.

Fig. 5 is a partial view in vertical cross-section taken longitudinally of Fig. 1 to illustrate the construction at the forward end of the magazine which is effective to provide a stop and a rear backing surface for the foremost staple of the staple strip.

Fig. 6 is an end view of the staple magazine.

Fig. 7 is a partial top view of the magazine.

Fig. 8 is a front view of the staple driving plunger.

Referring to Fig. 1, cam cylinder 3, which is not a part of plunger 5, contains a cam groove in which pin 4 travels. This groove is slotted through the cylinder to the opposite side, or may be on one side only. Pin 4 is pressed through a hole in plunger 5. Plunger 5 has a staple driving blade 6 secured to or a part of its end. This staple driving blade 6 is sized and shaped in such a manner that its bottom edge has the same contour as the top of the staple, and is thin enough to cause only one staple to be pushed through the end channel of the magazine 2, and on through the rotatable staple guide-way member 7.

2

Operation of the stapler to eject staples to either position X or position Y is as follows:

1. To eject staples to position X, shown in Fig. 1, trigger 8, Fig. 4, is pulled outward to remove the end of the trigger from the slot 13 in cam cylinder 3, see Fig. 1. Depressing the handle 9 moves plunger 5 downward, which causes staple driving blade 6 of the plunger 5 to carry a staple 1 through the end-channel of magazine 2 and on through the rotatable staple driving guide-way member 7. Cam cylinder 3 turns freely on plunger 5 since trigger 8 was disengaged from the slot 13 and as the driving of the plunger continues through member 7 the staple will be driven as shown at X in Fig. 1.

2. To eject staples to position Y, shown in Fig. 1, trigger 8, Fig. 4, is pushed in to engage slot 13, Fig. 1. Depressing the handle 9 moves plunger 5 downward. Since cam cylinder 3 cannot rotate, pin 4 moving in the groove of cam cylinder 3 causes plunger 5 to rotate. This rotation of plunger 5 is delayed until a staple 1 and the staple driving blade 6 of the plunger 5 have completely engaged rotatable staple driving guide-way member 7. This delay is accomplished by having the groove in cam cylinder 3 straight at each end, (top and bottom) for the necessary distance to delay rotation of plunger 5 on the downstroke, which in turn permits travel through the end channel of magazine 2. When the staple driving blade 6 of plunger 5 has passed into rotatable staple driving guide-way member 7, the pin 4 has reached that section of the groove of cam cylinder 3 which will cause ninety degree rotation of 5, 6, and 7, after which pin 4 travels in the bottom straight section of the cam cylinder groove. Plunger 5 and staple driving blade 6, therefore, cease to rotate, causing 7 to remain stationary and the staple is ejected in position Y.

40 Spring 14, Fig. 2, returns plunger 5 to its original starting position. As the plunger travels upward, there is no rotation of plunger 5 as long as pin 4 is in the straight section of the cam cylinder groove. Upon reaching the rotational section of the cam cylinder groove, the pin 4 causes the plunger 5 to rotate in the reverse direction ninety degrees, which in turn causes the staple driving blade 6 to rotate part 7 ninety degrees. This rotation places the staple-slot of part 7 parallel to and in line with the channel end of magazine 2, allowing the staple driving blade 6 to proceed upward to its starting position above the top of the first staple 1 in the magazine. Rotation ceased immediately before the staple driving blade 6 passed into the end channel of mag-

azine 2, due to the pin 4 being again disposed in the upper straight section of the cam cylinder groove.

Block 11, Fig. 5, is secured to plate 12 of the housing, Fig. 2. This block 11 aids in preventing jamming on the upstroke and downstroke. It also aligns the staple driving blade 6 of plunger 5 as the staple driving blade 6 moves upward out of the channel of magazine 2. Block 11 also prevents the second staple in the magazine from being forced upward on the upstroke due to any small misalignment of parts.

Having thus disclosed the invention, we claim:

1. In a staple driving assembly for a stapling machine, said assembly comprising, a staple driving plunger, means mounting said plunger for reciprocating movement, a rotatable cylinder in which said plunger reciprocates, a magazine for supporting a strip of staples with a foremost staple of the strip below the plunger to be driven thereby, a freely rotatable member having a staple receiving guideway mounted below the foremost staple, a pin extending transversely of the plunger, cam grooves in said cylinder for receiving the end of the pins, and means to prevent rotation of said cylinder whereby said plunger upon reciprocation to drive a staple will first move vertically to advance the staple into the guideway of said freely rotatable member and then rotate said driver and said member upon further advance of said plunger.

2. In a stapling machine, according to claim 1, means for releasing said cylinder rotation preventing means to permit free rotation of the rotatable cylinder whereby the plunger upon reciprocation to drive a staple will first move ver-

5 tically to advance the staple into the guideway of the freely rotatable member and then rotate said cylinder to permit said plunger to further advance without rotating said plunger or said freely rotatable member.

10 15 20 25 30 35 40 45 50 55 60 65 70 75 80 85 90 95

3. In a stapling machine, a magazine for housing a strip of staples, a vertical raceway for receiving the foremost staple of said strip, a driver for driving the foremost staple, means providing a guideway in line with and below said vertical raceway to receive the staple being driven, a guideway for said driver, means for guiding said driver in the driving of a staple, said last-mentioned means comprising means to rotate said driver in the movement of the driver to drive the staple.
